UNITED STATES PATENT OFFICE.

WILLIAM JULEN NELSON, OF BRANDON, SOUTH DAKOTA.

LATCH FOR SLIDING DOORS.

1,314,978.

Specification of Letters Patent.

Patented Sept. 2, 1919.

Application filed June 14, 1919. Serial No. 304,181.

To all whom it may concern:

Be it known that I, WILLIAM JULEN NELSON, a citizen of the United States, residing at Brandon, in the county of Minnehaha and State of South Dakota, have invented certain new and useful Improvements in Latches for Sliding Doors, of which the following is a specification, reference being had to the accompanying drawings.

10 This invention relates to an improved latch particularly adapted for use in connection with sliding doors, and the invention aims to provide a latch of this kind which is operable either from the inside or the outside of the closure.

15 The invention further aims to provide means secured upon the opposite faces of the door or closure and carrying spring tensioned hand grasps, operable from either 20 side of the door or closure, and one carrying a hasp or latch member, which is designed to enter the keeper, either secured to a second sliding door, or to a jamb of the door opening, for holding the door closed.

25 The invention further aims to provide a latch of this character, the hasp or latch member of which may be actuated from either side of the door, to disengage it from the keeper.

30 The invention further aims to provide guiding means for the hand grips or grasps, as they are moved, when being independently movable with relation to the other, which may be pulled inwardly to actuate 35 the former grasp or grip.

While the design and construction at present illustrated and set forth is deemed preferable, it is obvious that as a result of a reduction of the invention to a more practical form for commercial purposes, the invention may be susceptible to changes, and the right to these changes is claimed, provided they are comprehended within the scope of what is claimed.

40 The invention comprises further features and combination of parts, as will be hereinafter set forth, shown in the drawings and claimed.

In the drawings:

45 Figure 1 is a view in elevation showing a pair of sliding doors or closures, one of which may be, if so desired, interpreted as the jamb of the door opening.

50 Fig. 2 is a perspective view of the forward edge of a sliding door or closure showing the improved latch mechanism as applied.

Fig. 3 is a horizontal sectional view on line 3—3 of Fig. 1.

Fig. 4 discloses detail views of the keeper, and the means to which the keeper is connected.

Fig. 5 is a detail perspective view of a portion of the plate 17 showing the T-shaped lug 18.

Referring to the drawings 1 and 2 designates opposite sheet metal plates, which are secured by screws or the like 2, to the inner and outer faces of the door or closure, adjacent its free edge. These plates 1 and 2 at one of their ends are provided with lateral flanges 3, which overlie each other, and one of which overlies and engages the edge of the door or closure. These plates constitute means for supporting the latch mechanism.

Secured to the outer plate 1, as shown at 4, are bracket plates 5, through the lateral parts of which the pivot bolt 6 is secured, by means of a nut 7. Pivoted upon the bolt 6 is a hand grip or grasp 8, which is angular as shown, and carries a laterally extending ear 9 provided with a pin 10. This pin 10 extends through a slot 11 in the plate 1, and in surrounding relation to the pin and interposed between the ear and the plate is a coil spring 12, thereby so tensioning the hand grip or grasp as to hold it in its outermost position as shown clearly in Fig. 2.

The end of the grip or grasp opposite where it is pivoted is bent to form the right angle portion 13, which protrudes through the opening 14 in the plate 1. This opening 14 on its upper and lower edges is provided with inwardly turned flanges 15, which enter the opening 16 through the door, thereby not only constituting guides for the right angle 95 extending portion of the grasp or grip, but also constituting wear plates. Carried by a portion of this right angle part of the grip or grasp is a plate 17, the inner end of which is provided with a lateral T-shaped lug 18. The opening in the door, which is bound by the flanges of the opening in the plate 1, is large enough to permit of the free movement of the portion 19 of the right angle part, so that the latch or hasp 105 lug 20 (which is carried by the portion 19) can move far enough inwardly as to be disengaged from the keeper.

The plate 2 at one end is provided with an opening 22, and secured to the face of the 110 plate 2 adjacent the inner face of the door or closure is an arched or U-shaped plate 23.

This plate 23 may be riveted or otherwise secured to the plate 2 as shown, and the arch of the plate 23 enters a cavity or recess formed in the door proper. A second 5 hand grasp or grip 24 is provided, and one of its ends is pivoted upon a pin 25, which is mounted transversely of the arch of the plate 23, and this grasp or grip has a lug 26. A spring 26^a is interposed between the 10 last mentioned grip or grasp and the inner face of the arch of the plate 23, and is in surrounding relation to the lug, thereby holding the hand grip or grasp normally in the positions as shown in Fig. 3. The other 15 end of the hand grip or grasp has a lateral extension 27, the greater end portion of which is slotted as shown at 28 and is curved, so as to permit free movement of the grip or grasp. This lateral extension 27 passes 20 through an opening 29 in the plate 2. This opening 29 registers with a correspondingly positioned opening in the plate 1. The opening 29 is also provided with inwardly extending flanges 30, also acting as guides 25 and wear plates. The slot in the lateral extension 27 receives the lateral T-shaped lug of the former grip or grasp, so therefore it will be seen that when the hand grip or grasp adjacent the inner face of the door or closure 30 is pulled inwardly, the outer grip or grasp will be likewise moved, thereby disengaging the hasp or latch member from the keeper. The outer hand grip or grasp may be moved inwardly, to disengage the latch 35 or hasp from the keeper, without operating the hand grip or grasp adjacent the inner face of the door.

The keeper 31 comprises an angular plate 32, which is secured by screws or the like to 40 the edge of an adjacent sliding door or to the edge of the jamb of a door opening, preferably the latter. This angular plate 32 has a vertical slot 34, and the keeper proper comprises a plate 35, which has a slot 36 for 45 the reception of the latch or hasp of the outer grip or grasp, to hold the door latched. The latch or hasp consists of an angular metal strap secured in place to a part of the angular portion of the outer grip or grasp, 50 and is adapted to receive a padlock or other locking means, that is after it has passed through the slot in the keeper proper in order to lock the door. The keeper plate proper is provided with an additional slot 55 37, which is disposed so that when the keeper plate proper is fastened to the angular plate, the slot 37 will be disposed at right angles to the slot in the angular plate. A suitable bolt 38 including a nut engages 60 through the two slots, so as to clamp the keeper plate to the angular plate. Whenever the angular plate is secured, either to a sliding door or to the jamb portion of the door opening, the portion to which it is secured is recessed, so as to permit of the

reception of the head of the bolt that secures the keeper plate to the angular plate. The keeper plate proper may be adjusted toward and from the latch or hasp or may be adjusted vertically, and by this adjustability 70 of the keeper plate proper, the keeper plate may be arranged to accommodate itself to the sagging of the door, or the separation of the meeting edges of the door or the meeting edge of one door relatively to the edge jamb 75 of the door opening.

The invention having been set forth, what is claimed as new and useful is:

1. In a latch mechanism for closures, the combination with mounting plates secured 80 to the inner and outer faces of the closure and provided with registering openings, of a pair of hand grips or grasps pivotally mounted upon said plates and being movable in a horizontal plane, said hand grips or 85 grasps having a sliding connection with each other, through said openings and through the closure, one of said grasps or grips having a latch or hasp engaging through one of the plates, and a keeper to receive the 90 latch or hasp.

2. In a latch mechanism, the combination with holding plates secured to the opposite faces of the closure, of a keeper either secured to a second closure or to the jamb of 95 an opening, a latch or hasp to engage the keeper, and opposing members movable in a horizontal plane relatively to the closure, one carrying the latch or hasp and being operable from one side of the closure, the 100 other having a loose connection with the former and being operable from the opposite side of the closure for operating the hasp or latch to disengage it from the keeper.

3. In a latch mechanism, the combination 105 with holding plates secured to the opposite faces of the closure, of a keeper either secured to a second closure or to the jamb of an opening, a latch or hasp to engage the keeper, and opposing members movable in 110 a horizontal plane relatively to the closure, one carrying the latch or hasp and being operable from one side of the closure, the other having a loose connection with the former and being operable from the opposite 115 side of the closure for operating the hasp or latch to disengage it from the keeper, and spring tensioning means for both members to hold them in normal positions.

4. In a latch mechanism, the combination 120 with a closure having an opening near its edge, of a pair of plates secured to the opposite face of the closure and having flanges overlying each other and engaging the edge of the closure, thereby covering the opening, 125 said plates having guide flanges extending into the opening of the closure, a keeper adjustably carried by a second closure or the jamb of the door opening, a hasp or latch to engage said keeper, opposing members pivot- 130

ally mounted upon said plates and being operable through the opening of the plates and guided by the flanges of said openings, one of said members carrying the latch or hasp 5 and being movable in a horizontal plane relatively to the closure to disengage the hasp or latch from the keeper, the other likewise being movable relatively to the closure, said opposing members having a sliding connection with each other at a point through the 10

opening of the closure, whereby either of said members may be actuated to disengage the hasp or latch from the keeper, and spring tensioning means for the opposing members.

In testimony whereof I hereunto affix my 15 signature in the presence of two witnesses.

WILLIAM JULEN NELSON.
